METHOD OF MAKING HINGES

Filed March 27, 1925

Patented May 15, 1928.

1,670,170

UNITED STATES PATENT OFFICE.

JOSEPH SOSS, OF BROOKLYN, NEW YORK.

METHOD OF MAKING HINGES.

Application filed March 27, 1925. Serial No. 18,716.

This invention relates to hinges and particularly to what are known as covered joint hinges; and the object of the invention is to so fashion a hinge of the class specified and in accordance with the method hereinafter more fully set out, from sheet metal, as to provide a strong and durable hinge joint for one butt of a hinge; and with this and other objects in view, the invention consists 10 in a hinge of the class specified and in the improved method of producing the same as set out in the specification and claims.

The invention shown and described herein is an improvement on that shown and described in a companion application filed by me March 9, 1924, Serial No. 14,037, and another application filed of equal date herewith, now Patent No. 1,614,262 dated Jan. 11, 1927, and is fully disclosed in the following specification, of which the accompanying drawing forms a part, in which the separate parts of my improvement are designated by suitable reference characters in each of the views, and in which:—

25 Fig. 1 is a face view of a part of a hinge made according to my invention.

Fig. 2 is a face view of a part of a blank from which one butt of the hinge shown in Fig. 1 is formed.

30 Fig. 3 is a side edge view of the blank shown in Fig. 2 partially formed.

Figs. 4 and 5 are views showing the steps of rolling one end portion of the blank shown in Figs. 2 and 3.

35 Fig. 6 is a plan view showing the next step in forming the hinge butt from the blank shown in Fig. 2.

Fig. 7 is a side view of the structure shown in Fig. 5 after the hinge has been 40 trimmed and partially shaped and sized.

Fig. 8 is a sectional view through both butts of the hinge shown in Fig. 1, in extended position, and showing in section the butt formed by the process represented in Figs. 2 to 7 inclusive.

45 Fig. 9 is a perspective view of one end portion of a partially formed blank and showing a modification of the structure shown in Figs. 1 to 8 inclusive.

50 Fig. 10 is a side edge view of the structure shown in Fig. 9 when partially formed.

Fig. 11 is a sectional view of a hinge butt showing the complete form of the part of said butt formed from the blank shown in 55 Fig. 9.

Fig. 12 is a side edge view of a part of a

hinge butt made from a blank similar to that illustrated in Fig. 2 and showing a modification in the formation of the rolled end portion thereof; and,

Fig. 13 is a side edge view of a part of the completed hinge butt formed from the structure shown in Fig. 12.

In Figs. 1 to 8 inclusive, I have shown one form of hinge butt made in accordance with my invention and illustrating one method of procedure and in Figs. 1 and 8, the separate butts of the hinge are designated by the numerals 14 and 15, but my invention relates primarily to the method of forming the 70 outer butt member 15 of the hinge and still more particularly to the formation of the pintle bearings or hinge joint of said butt member.

In Fig. 2 of the drawing, I have shown one end portion of a blank 16 which is of the same dimensions throughout its length and in practice, one end portion of the blank is cut out at the corners thereof as shown at 17 to form a projecting tongue member 18 arranged centrally of the blank 16, and the free edge of said tongue member is preferably beveled or rounded as shown at 19 in Fig. 3 of the drawing. The next step in forming the butt from the blank shown in Fig. 2 consists in rolling the end portion of the blank provided with the tongue 18, and said tongue, substantially into the position shown in Fig. 4 of the drawing where the free beveled edge 19 is in close proximity to the upper face of the blank in such manner as to form a comparatively small aperture 20 extending through the curved or rolled portion of the blank thus formed. The next step consists in further rolling the blank to form a substantially cylindrical body of the tongue end portion of the blank and providing two thicknesses of metal at the outer face of the blank and also in forming a curvature 21 in the blank adjacent the cylindrical portion.

After the curling or rolling operations above referred to, the product thus formed is swaged or compacted by placement in suitable dies and subjected to great pressures when the workpiece or blank 16 as formed, is cold or heated as desired, and said workpiece is fashioned to force the cylindrical portion inwardly and to flatten the curled side portions 22 of the blank at the opposite sides of said cylindrical portion to reduce the thickness of said side portions and

to form recesses adapted to receive the knuckles 14^a of the hinge butt 14 and also to properly size and compactly form said cylindrical portion to produce a pintle bearing 23. In the above operation, the flattening of the side portions 22 form at the opposite sides of the bearing 23, laterally extending walls 24 forming the hood proper or means for covering the joint of the hinge or for partially concealing the knuckles 14^a of the butt 14 as will be apparent.

After the last named operation, the flarings of metal 25 are trimmed off, and in the final operation, the finish sizing and shaping of the curved pintle bearing portion of the hinge butt is formed after which the aperture for receiving the pintle pin 26 is drilled through the bearing 23 and the side faces of said bearings cleaned off by a suitable tool to render the same smooth and of perfect alinement to function with the knuckles 14^a, it being also understood that the recesses at the opposite sides of the bearing 23 may also be cleaned out for this purpose if the same is found to be necessary. The offsetting of the shank 27 of the butt, as represented in dotted lines in Fig. 4 and full lines in Fig. 7, may be performed if desired in the several operations of forming the hinge butt 15, and if so fashioned, it will be understood that the shank is returned to proper position after the butt has been completely formed.

In the above described method, if the workpiece be heated, it will be understood that the entire curved end portion of the hinge butt and particularly the bearing 23 thereof will be formed into substantially a solid unitary mass, while if the same is formed cold, the metallic mass will be compactly swaged or pressed together under pressure in the proper shaping of the hinge butt.

In Figs. 9, 10 and 11, I have shown a slight modification in the formation of the hinge butt 15 wherein the bearing 23 is formed by a plurality of independent members 28 rather than from the tongue 18, and in this construction, in addition to the butt 15 which will constitute one part only of the butt, is employed a shell or facing member 29. The parts or extensions 24 of the structure shown in Figs. 1 to 8 inclusive are not employed, said facing having a hood portion 30 which takes the place of the members 24. The structure shown in Fig. 11 is substantially the same as that shown and described in Patent No. 1,477,193, granted to me December 11, 1923, with the exception that the bearing portion 31 of the hinge butt formed by the members 28 is of greater strength due to the method of its formation which will be the same as that described in connection with the butt shown in Figs. 1 to 8 inclusive.

In Figs. 12 and 13, I have shown another

modification in which a blank similar to that shown at 16 in Fig. 2 of the drawing is employed, the cut out portions 17 being cut deeper into the material of the blank to form a longer tongue 18 and to increase the 70 rolling or turning operaton on the blank to such a degree as to provide throughout the entire curved end portion of the hinge substantially two thicknesses of metal, the bevelled end portion 19 extending to such a point 75 as to provide substantially two complete turns of the tongue member 18. After the blank has been formed substantially in the manner illustrated in Fig. 12 of the drawing, the same is preferably heated and then 80 placed in dies which will shape the curved end portion of the hinge into a form substantially similar to that illustrated in Fig. 13 of the drawing forming a large, heavy 85 pintle bearing 32, the inner edge of which 90 extends to the top face 33 of the butt as shown at 34, reinforcing and strengthening the bearing 32 at this point. Recesses 35 will be formed at the opposite sides of the bearing 32 similar to the structure shown in 95 Figs. 5 and 7 of the drawing, said recesses being adapted to receive the knuckles of the other butt of the hinge, while the butt is extended and gradually reduced to form projecting hood members 36 at the opposite 100 sides of the bearing 32 closing the recesses 35 and enclosing or partially enclosing the knuckles of the other butt of the hinge, the free edges 37 of the hood members 34 constituting a stop for limiting the movement 105 of the other butt of the hinge.

After the butt has been formed in the manner shown in Fig. 13 of the drawing and by the heat process, the rolled metal will be formed into one substantially integral mass 110 which is drilled to form the pintle aperture 38 and the recesses 35 and side faces of the bearing 32 may be cleaned out by a suitable tool if required. It will also be seen that the shoulder or stop 37 extends through 115 the bearing 32 and this is also true of the structure shown in Figs. 1 to 8 inclusive.

From the method herein described and illustrated in the accompanying drawing, it will be apparent that the pintle bearing of the hinge butt will be made very strong and durable and capable of withstanding the greatest stress or stresses and will be as strong as, or even stronger than hinges of this class fashioned from castings, forgings 120 and the like and may be produced at much less expense as compared with the other methods of forming hinges of this class, and while I have shown and described certain methods of carrying my invention into effect 125 and have illustrated hinge butts of specific construction, it will be understood that my invention is not limited in these respects and various changes in and modifications of the method herein set out may be made within 130

the scope of the appended claims without departing from the spirit of my invention or sacrificing its advantages.

Having fully described my invention, what

5 I claim as new and desire to secure by Letters Patent, is:—

1. The herein described method of fashioning a hinge butt from sheet metal to provide at one end of the butt a curved hood portion with a pintle bearing within said hood portion, which consists in providing a rectangular sheet metal blank, cutting out 10 the corner portions of said blank to form a projecting tongue at one end thereof, curling said tongue and adjacent end portion of the blank to curl the tongue upon itself a number of times to form a thick cylindrical member and a curved hood portion partially 15 encircling said member and extending at opposite sides thereof, and then compacting said cylindrical member to form a substantially solid pintle bearing within said hood member.

2. The herein described method of fashioning a hinge butt from sheet metal to provide at one end of the butt a curved hood portion with a pintle bearing within said hood portion, which consists in providing a rectangular sheet metal blank, cutting out 20 the corner portions of said blank to form a projecting tongue at one end thereof, curling said tongue and adjacent end portion of the blank to curl the tongue upon itself a number of times to form a thick cylindrical member and a curved hood portion partially 25 encircling said member and extending at opposite sides thereof, then compacting said cylindrical member and hood portion to form a substantially solid pintle bearing within said hood member, and forming in said compacting operation recesses in said hood portion and at opposite sides of said pintle bearing to receive the knuckles of the other butt of a hinge.

45 3. The herein described method of fashioning a hinge butt from sheet metal to provide at one end of the butt a curved hood portion with a pintle bearing within said hood portion, which consists in providing a rectangular sheet metal blank, cutting out 50 the corner portions of said blank to form a projecting tongue at one end thereof, curling said tongue and adjacent end portion of the blank to curl the tongue upon itself a number of times to form a thick cylindrical member and a curved hood portion partially 55 encircling said member and extending at opposite sides thereof, then compacting said cylindrical member and hood portion to form 60 a substantially solid pintle bearing within said hood member, and forming in said compacting operation recesses in said hood portion and at opposite sides of said pintle bear-

ing to receive the knuckles of the other butt of the hinge, and then forming the pintle pin 65 aperture in said pintle bearing.

4. The herein described method of making the butt of a hinge which consists in providing a sheet metal blank having at one end portion thereof a projecting member of less transverse dimensions than the remainder of the blank, curling said member and adjacent portion of the blank to form a cylindrical member of greater thickness than the thickness of the blank and a hood portion 70 partially encircling said member and extending at opposite sides thereof, heating the blank thus formed, and then swaging said cylindrical member to form a substantially solid pintle bearing within said hood portion.

5. The herein described method of making the butt of a hinge which consists in providing a sheet metal blank having at one end portion thereof a projecting member of less transverse dimensions than the remainder of the blank, curling said member and adjacent portion of the blank to form a cylindrical member of greater thickness than the thickness of the blank and a hood portion 75 partially encircling said member and extending at opposite sides thereof, heating the blank thus formed, and then swaging said cylindrical member to form a substantially solid pintle bearing within said hood portion.

6. The herein described method of making the butt of a hinge which consists in providing a sheet metal blank having at one end portion thereof a projecting member of less transverse dimensions than the remainder of the blank, curling said member and adjacent portion of the blank to form a cylindrical member of greater thickness than the thickness of the blank and a hood portion 80 partially encircling said member and extending at opposite sides thereof, heating the blank thus formed, and then swaging said member and hood portion at the opposite sides of said member to form of said member a cylindrical pintle bearing and recesses in the hood portion at the opposite sides of said bearing, the walls of said recesses being of less thickness than the metal of the blank.

100 7. The herein described method of making the butt of a hinge which consists in providing a sheet metal blank having at one end portion thereof a projecting member of less transverse dimensions than the remainder of the blank, curling said member and adjacent portion of the blank to form a cylindrical member of greater thickness than the thickness of the blank and a hood portion 105 partially encircling said member and extending at opposite sides thereof, heating the blank thus formed, and then swaging said member and hood portion at the opposite sides of said member to form of said member a cylindrical pintle bearing and recesses in the hood portion at the opposite sides of said bearing, the walls of said recesses being of less thickness than the metal of the blank, and forming in said swaging operation, a stop shoulder on the pintle bearing portion 110 of the butt and in alinement with the free edge of the hood portion.

In testimony that I claim the foregoing as my invention I have signed my name this 13th day of March 1925.

JOSEPH SOSS.
